UNITED STATES PATENT OFFICE.

GUY B. FITZ, OF AUBURN, MAINE, ASSIGNOR TO FITZ-EMPIRE DOUBLE PIVOT LAST COMPANY, OF AUBURN, MAINE, A CORPORATION OF MAINE.

LAST.

Application filed May 14, 1925. Serial No. 30,209.

This invention relates to shoe lasts and is illustrated as embodied in a last of the type disclosed in United States Letters Patent No. 784,149, granted March 7, 1905, on application of A. G. Fitz.

In the manufacture of certain types of shoes, of which strap sandals furnish a good example, it is necessary that the lasts used be of the type having what is termed a "full cone"; that is, that the upper front surface of the cone of each last extend from the ball to a point at or beyond where the instep portion of the shoe upper rises substantially vertically, or, in the case of shoes such as strap sandals, to a point beyond where the strap of a sandal on the last engages the upper front surface of the cone, in order to afford adequate support for the shoe upper for lasting and other shoemaking operations.

Lasts as heretofore constructed have not been satisfactory for use in making strap sandals and other shoes presenting similar problems. While it is practicable and is usual to make block lasts with full cones, block lasts are liable to damage shoes when they are removed, particularly shoes having vamps cut with narrow throats with which many strap sandals are provided, since it is not practicable to make the movable instep block of a block last large enough to insure against straining or tearing shoe uppers when the last is removed unless the block is made so large as to weaken the body part of the last too much. Consequently, hinge

lasts, which may be shortened sufficiently to provide for removal from the shoes without damaging the shoe uppers, have come into extensive use. The relative swinging movement of the foreparts and heel parts necessary to collapse the practical forms of hinge lasts requires, however, that there be a substantial space between these parts, and as such lasts have heretofore been constructed, this space has been provided as a V-shaped notch so located as to shorten the upper front surface of the last as compared with a full cone last. The result has been that it has been difficult in the use of such lasts to afford the proper support for various types of strap sandals having straps designed to pass over the foot in the region corresponding to the top of a full cone. Sometimes it has been attempted to remedy this difficulty by pull-

ing the strap down into the notch and tacking it there, but this often crushes or otherwise damages the strap and sometimes pulls the upper out of shape. When this expedient is not resorted to, there is liability that the strap will slip into the notch, particularly when the upper is under tension in the lasting operation, thus relaxing the lasting tension and preventing proper lasting.

It has been proposed heretofore to make hinge shoe forms with continuous full cones, the forepart being cut away and the upper front portion of the heel part being arranged to be moved into the cut-away portion of the forepart to collapse the forms, but such articles, while adequate as forms, were not intended and have not been adapted for use as shoe lasts because the pivots of the hinges or bonding mechanisms between the foreparts and heel parts were placed so high as to cause the forms to lengthen substantially before they began to shorten. Consequently, the lower rear end portions of the forms were cut away in order to permit removal of the forms from the shoes. Moreover, it is not practicable to lower the pivot of such a construction sufficiently to permit the use of a full-sized form such as might be adapted for use as a last without cutting away so much wood to provide for the collapsing movement as to weaken the structure excessively.

In view of the foregoing, it is an object of the present invention to provide a practical last of full shape and strong enough to resist adequately the stresses of machine shoemaking which will be so constructed and arranged as to afford proper support, for example, for the straps of strap sandals and which will have all the advantages of hinge lasts as heretofore constructed.

To this end, the invention provides a novel hinge last having a full cone presenting a substantially continuous surface along the upper front portion of the cone from the ball rearwardly considerably beyond the cut between the forepart and the heel part when the last is extended, the heel part and forepart being relatively shaped to have the upper portion of one brought into overlapping relation to the upper portion of the other, thereby collapsing the last sufficiently to insure ready removal from the shoe with-

out danger of damaging the shoe upper. Preferably, and as herein illustrated, the upper front portion of the heel part is provided with a recess and the upper rear portion of the forepart is adapted to enter that recess, thereby collapsing the last, the upper front portion of the heel part overlapping the upper rear portion of the forepart and projecting outwardly beyond the contour of a shoe on the last when the last is collapsed. By this construction and arrangement there is provided a full-cone hinge last which is constructed and arranged to be collapsed sufficiently for ready removal from shoes without sacrifice of last strength, the amount of wood removed to form the necessary space between the forepart and heel part being reduced to a minimum, and the forepart and heel part are relatively shaped to provide the necessary space between them without interrupting the continuity of the upper front surface of the cone when the last is extended.

These and other features of the invention, comprising certain combinations and arrangements of parts, will be understood from the following description of a preferred embodiment thereof selected for purposes of illustration and shown in the accompanying drawings, in which,

Fig. 1 is a longitudinal cross section of the last, and

Fig. 2 shows the last with a strap sandal on it.

The illustrated last comprises a forepart A and a heel part B connected by a hinge bonding mechanism substantially like that of the last shown in the United States Letters Patent above referred to. The forepart A and heel part B, which are so shaped as to provide a full cone, as above described, are separated upon a line which cuts across this cone at a considerable distance from its upper end and runs at an angle of roughly 45° downwardly and backwardly from the upper instep portion of the last to a point about three-quarters of the way through the last, as indicated by the numeral 10. It then extends backwardly generally horizontally for a short distance, as indicated by the numeral 12, to provide a shelf for holding the last parts positively in alignment and then runs downwardly and a little backwardly as indicated by the numeral 14, to the lower surface of the last. The heel part is cut away from a point 16 on the cut 10 about half or two-thirds way through the last, upon a surface 18 which is intersected by a surface 20 overhanging the surface 18, which runs out and intersects the front of the instep of the last at the beginning of the cut 10. The two planes 18 and 20 form a recess in the front face of the heel part. The heel part and forepart are connected by pivoted links 22, 24 mounted on pins in the heel part

and forepart as shown in the Letters Patent referred to and the upper link has a projection 26 engaging a spring 28 to hold the last parts resiliently in extended position as likewise shown in that patent.

Fig. 1 shows in dotted lines the position of the last parts in collapse. When in this position the heel part swings upwardly and forwardly until the surface 18 abuts against the surface 10, the deepest point of the recess formed by the intersection of the surfaces 18 and 20 being arranged to come at the forward end of the surface 10, and the overhanging portion of the heel part moving forward beyond the outline of the shoe.

It will thus be seen that when the last is extended the front upper surface of the cone of the last is continuous from the ball back beyond the cut between the forepart and heel part to the point 30, and indeed, the point 30 can be placed as far to the rear as is desired, since all of the portions of the last that are concerned in the collapsing movement lie well below it. The wood taken from the last as shown is represented by the outline formed by the lines 10—18—20. The angle between the planes 10 and 18 is substantially the angle through which the heel part swings on the forepart in collapse, and these planes are so located that they come substantially into coincidence when the last is collapsed. The line 20 represents substantially the movement of the end point of the cut 10 on the forepart, relatively to the heel part. Thus there is no substantial aperture in the front of the cone at the cut to catch or pinch the upper of a shoe and the wood taken from the last is reduced to a minimum amount and is much less than is required in a construction, for example, where the heel part collapses into the forepart, since with the present construction no room has to be provided anywhere in the last to receive the overhanging portion of the heel part in collapse.

The advantages of the last will be evident from a consideration of Fig. 2 which shows one type of strap sandal in position on the last. The sandal shown is that type in which an instep strap 32 runs around the foot and engages a strap 34 running down the front of the shoe into the vamp. The strap 30 is here so high that the ordinary hinge last would provide no support for it at all, and it would have to be left loose or else pulled down into the V cut between the last parts, with liability to damage and also to distortion of the upper. The strap 34 would get no support at all with such a last, and indeed, has heretofore been simply doubled down under the vamp and neglected, the lasting of the waist portion of the shoe suffering accordingly.

The last of the present invention avoids all such difficulties, and provides a strong

hinge last supporting any type of shoe upper at all points as adequately as a solid last could do.

Having described my invention, what I claim as new and desire to secure by Letters Patent of the United States is:—

A hinge last comprising a heel part and a forepart relatively constructed and arranged to provide a full cone having a substantially continuous surface along the front upper portion of the last from the ball to the tip of the cone when the last is extended, the upper rear face of the forepart being in a plane intersecting said continuous surface and the upper front face of the heel part being in two intersecting planes form-

ing a recess in said face, and bonding mechanism comprising two links, one above the other, each pivoted in both last parts, and constructed and arranged to effect relative movement of the heel part and the forepart, so arranged as to bring the upper rear face of the forepart substantially into the lower of the planes forming the recess while the upper rear edge of the forepart is substantially grazed by the portion of the front surface of the heel part in the upper of the two planes forming the recess. 20
25

In testimony whereof I have signed my name to this specification.
